UNITED STATES PATENT OFFICE.

JOSEPH ROI MARCHESEAU, OF WORCESTER, MASSACHUSETTS, ASSIGNOR TO
WORCESTER PRESSED STEEL COMPANY, OF WORCESTER, MASSACHUSETTS, A
CORPORATION OF MASSACHUSETTS.

PRESSED-STEEL PULLEY.

1,329,790.

Specification of Letters Patent.

Patented Feb. 3, 1920.

Application filed June 7, 1919. Serial No. 302,453.

To all whom it may concern:

Be it known that I, JOSEPH ROI MARCHESEAU, a citizen of the United States, residing at Worcester, in the county of Worcester and State of Massachusetts, have invented new and useful Improvements in Pressed-Steel Pulleys, of which the following is a specification.

This invention relates to the manufacture of pulleys and wheels from sheet metal, and more particularly to sectional or split pulleys made of pressed steel, and its object is to produce a pulley which will have maximum strength with relatively small weight, which can be mounted on or removed from a shaft quickly and easily without the necessity of disturbing other pulleys adjacent to it on the same shaft, which will be clean and have no projecting parts to catch in anything and, generally, which will be a "safety" pulley to a high degree.

While certain features of the construction can be advantageously used in solid wheels and pulleys, the preferred form of the invention is the split pulley, in which all the advantages of the improved construction are fully realized.

The invention is illustrated in the accompanying drawing, in which, Figure 1 is a cross section of the preferred form of pulley, or it may be considered as a front view of one half of a split pulley; Fig. 2 is a side elevation of the same, with one half in section; Fig. 3 is a view similar to Fig. 1 of a modified construction, suitable for small pulleys, and Fig. 4 is a similar view showing a construction suitable for a solid or non-split pulley or wheel.

I will first describe the split pulley shown in Figs. 1 and 2. The outer members comprise the rim portions 1, 1, and the concave web portions 2, 2. The latter have a semi-circular opening 3, inwardly flanged as at 4, which fits around the half bushing 5. Each inner member consists of a conical disk or web portion 6, which also has a semi-circular opening 3, outwardly flanged as at 9, to fit the bushing, a short radial portion 7, and an outwardly extending flange 8 on the latter. The radial portions 7, 7, of the two inner members are placed back to back and united by spot welding, riveting, bolting, or the like, and the rim portions 1, 1, of the two outer members are similarly secured to the

flanges 8, 8. Prongs 13 are formed on the clamps 10, which pass through holes in the flange and bushing and are riveted over on the inside of the latter, as shown in Fig. 1.

Fig. 2 illustrates a construction for a small wheel or pulley, in which the inner members may be omitted. It consists of two members each having a rim portion 15 and a web portion 16, the latter being centrally cut away to fit over the bushing 5 and having a flange 17 around the said opening. A ring 18 is placed inside the rim portions at their meeting edges and is secured there by welding or equivalent means.

This form may be used in a split pulley or in a solid one. When in the former, the same kind of clamps are used to clamp the pulley on the shaft as are used in Figs. 1 and 2, in which the semi-circular clamp members are indicated at 10 and the clamp bolts at 11. The bolts are actuated by a socket wrench inserted through the openings 12, formed in the rim portions of the outer members for that purpose.

A somewhat different form of construction is shown in Fig. 4, adapted for a solid pulley, but more especially for wheels of trucks, such as are used in manufacturing shops. Here the rim portion 20 of one outer member lies wholly within the rim member 20 of the other outer member. Each outer member comprises the web portion 21, which may be concaved or not, as desired, and which has the inwardly flanged opening 22 for the hub or bushing 5. Each inner member comprises the conical portion 23, the radial portion 24 and the peripheral flange 25, secured to the inner rim portion 20. In this form the flanges 26 on the inner members extend inwardly and conform to and fit in the flanges 27 of the web portions of the outer members.

It will be noticed that these pulleys present unbroken smooth external surfaces, whereby the danger of catching one's clothing is obviated, the placing of a belt is rendered easier and safer, and the pulleys can even be cleaned while running.

The absence of all external seams, joints, or gaps, as in the ordinary split pulley, makes a cheaper, truer running, better balanced and stronger pulley than any heretofore on the market, as far as I am aware. The meeting edges of the rim portions may

be spun into the groove between the radial portions and welded so that the surface of the rim is left perfectly smooth.

The pulley, although light, is extremely strong.

Having thus described my invention, what I claim is:

1. A sheet metal wheel or pulley comprising two outer members, each consisting of 10 a rim portion and an external web portion, the latter having a flanged central aperture, and two inner members, each consisting of a conical web portion having a short radial portion and a flange at its periphery and 15 also having a flanged central aperture, and a bushing fitted in said apertures, all said parts being permanently united at meeting points.

2. A split pulley, each half of which comprises 20 a semi-circular bushing and two semi-circular pressed steel members, each comprising a rim portion and an external web portion, the meeting edges of said rim portions being united together and the web 25 portions being apertured to fit over said bushing and connected thereto, and clamps fitting over the bushing to attach the two halves of the pulley together, said rim portions being apertured to permit access to 30 said clamps.

3. A split pulley, each half of which is built up of two pressed steel members having 35 integral rim and web portions, two inner pressed steel conical members placed back to back and united to said rim portions, and a half bushing, said web portions and conical members being apertured to fit said half bushing and connected thereto, and clamps fitting over the bushing to attach 40 the two halves of the pulley together, said rim portions being apertured to permit access to said clamps.

4. A split pulley, each half of which consists of two rim members having integral 45 external semi-circular webs with inwardly flanged semi-circular central apertures; two conical disk spoke members having outwardly flanged semi-circular central apertures and peripheral flanges united to said rim members; and a half bushing secured 50 within said apertures, said rim members provided with openings to enable the halves to be assembled on a shaft.

5. A split pulley, each half of which is built 55 up of two outer members, two inner members, and a half bushing, each outer member comprising a rim portion and an external web portion, and each inner member comprising a conical portion, a peripheral flange, and a short radial portion connecting said flange to said conical portion, said web and conical portions being recessed to fit said half bushing, and clamp

members fitting around said half bushing between said web and conical portions to 65 connect the two half pulleys together, said rim portions having openings to give access to said clamps.

6. A split pulley, each half of which consists of four pressed steel parts and a half bushing, all united by spot welding or the like, two of said parts constituting the outer or rim members and the other two the inner or spoke members, each outer member consisting of a rim portion and an external web portion, the latter being recessed to fit over said half bushing, and each inner member consisting of a conical web portion, recessed to fit over said half bushing, a short radial portion and a flange on the latter, 80 said flanges fitting within the meeting edges of said rim portions and said radial portions of the two inner members contacting with each other, and said rim portions having openings to permit access to means to 85 clamp the two half pulleys together on a shaft.

7. A wheel or pulley built up of two outer and two inner pressed steel parts and a bushing, each of the outer parts consisting 90 of a rim portion and a concave web portion, having an inwardly flanged central opening to receive said bushing, and each of the inner parts consisting of a conical portion, having an outwardly flanged central opening 95 to receive said bushing, a short radial portion, and a peripheral flange on the latter, said flanges being permanently connected to the meeting edges of said rim portions and said radial portions being permanently connected together. 100

8. A split pulley comprising pressed steel outer members, each having a rim portion and an external web portion, and pressed steel inner members comprising web portions supporting said rim portions, and clamps to unite the halves of the pulley located between the web portions of the outer members and the web portions of the inner members, whereby they are concealed and 110 protected, said rim portions being apertured to permit actuation of said clamps.

9. A split pulley each half of which consists of a semi-cylindrical hub member, two pressed steel, semi-circular web members, 11 having flanges constituting rim portions, fitted on the ends of said hub member, a reinforcing member between said web members and secured on the inside of said rim portions, and clamping means on said hub member to secure the two half pulleys together, said rim portions being apertured to permit access to said clamping means.

In testimony whereof I have hereunto set my hand.

JOSEPH ROI MARCHESEAU
